SHOE CLAMP

Filed Oct. 30, 1923

Fig. 1.

UNITED STATES PATENT OFFICE.

EMMETT W. ENTRIKEN, OF BALTIMORE, MARYLAND.

SHOE CLAMP.

Application filed October 30, 1923. Serial No. 671,685.

This invention relates to certain new and useful improvements in shoe holding clamps, particularly designed to be connected to a shoe shining stand so as to retain the foot 5 and shoe of a person from accidentally slipping or moving off the stand.

Another object of this invention is the provision of a shoe clamp adapted to be secured to a shoe shining stand and capable 10 of being adjusted vertically and longitudinally to permit it to be readily fastened to various sized shoes to retain the latter against accidental displacement from the stand.

15 A still further object of this invention is the provision of a shoe clamp permanently secured to a shoe shining stand and so constructed as to permit it to be raised and lowered vertically with relation to the foot plate 20 of the stand and moved longitudinally relative to said shoe supporting plate so that said clamp may be fastened to a shoe at different points and retain said shoe against slipping from said stand.

25 A still further object of the invention is the provision of a clamp capable of being secured to a shoe shining stand and located wholly beneath the foot rest of the stand so as to be out of the way and not form any 30 obstructions during the shining process of the shoes resting on the stand.

Another object of this invention is the provision of a shoe clamp for shoe shining stands, which can be manufactured at a comparatively small cost and easily applied to 35 any of the known stands now in use.

With these and other objects in view, the invention consists in certain novel features, combination and arrangement of parts as 40 will be hereinafter more fully described, pointed out in the drawing, and claimed.

In the drawing,

Figure 1 is a top plan view of the foot plate of a shoe shining stand showing parts 45 of my invention in dotted lines and its application with relation to a shoe supported on the stand.

Figure 2 is a side elevational view of my improved shoe clamp as made in accordance 50 with this invention.

Referring to the drawing, the numeral 5 indicates a support of a shoe shining stand commonly found in all shoe shining parlors,

and this stand is provided at its upper end with a shoe supporting plate 6, and upon 55 this shoe supporting plate the shoes of a person are supposed to rest while being shined. Heretofore during the process of shining the shoes indicated by the character "a" in the drawing, it was impossible to retain the shoe on the plate 6, and to overcome this serious objection has been the thought and aim of the present invention.

The present invention includes in its construction a collar or band 7, which is secured to the stand 5 by suitable fastening means 8, such as bolts, screws, or the like, and this collar or band is provided with supporting ears 9 in which is pivotally secured at one end as at 10, a supporting arm 11, and to the forward end of this supporting arm 11 is a second arm 12. The arm 12 is pivotally secured by one of its ends as at 13, to the free end of the arm 11, and these pivoted points 10 and 13, respectively, permit vertical and lateral movements of the arms 11 and 12, respectively.

To maintain the arm 11 in a substantially horizontal position, I provide a spring 14, which has one end secured as at 15, to the 80 collar or band 7, while its free end is normally in contact with the underside of the arm 11, consequently normally urging this arm upwardly. This spring 14 has a tendency to keep the arms 11 and 12 up in the 85 direction of the shoe plate 6 of the stand 5, the purpose of which will be hereinafter more fully described.

To maintain the arm 12 substantially in a vertical position, and at the same time permit it to have longitudinal, reciprocating motion relative to the foot plate 6, I provide a pair of springs 16 and 17, respectively. The spring 16 has one end secured as at 18 to the upper side of the arm 11 and has its 95 free end normally in contact with the inner side edge of the arm 12, and the spring 17 has one end secured as at 19 to the under side of the arm 11, while its free end is curved upwardly into contact with the outside, longitudinal edge of the arm 12. This relative positioning of the springs 16 and 17, respectively, normally maintain the arm 12 approximately in vertical position with relation to the stand 5, but at the same time 100 it permits the arm 12 to be moved either in-

wardly or outwardly with relation to the stand 5, and the purpose of which will be hereinafter more fully described.

To retain the shoe "a" against accidental displacement from the foot plate 6, I secure to the upper end of the arm 12 a clamping means 20.

This clamping means 20 comprises in its construction a rectangular housing member 21, which is pivotally secured as at 22 to the upper end of the arm 12 and is locked thereto by a suitable key 23.

Extending longitudinally through the housing 21 and journaled in the end walls 15 thereof is a right and left handed threaded bar 24, and mounted on this bar are threaded nuts 25, and these nuts have secured thereto by suitable links 26, the shoe clamps 27.

The clamps 27 are pivotally secured as at 20 28 to the free ends of a pair of the links 26, and the free ends of each pair of links are in turn pivotally secured as at 29 to the nuts 25.

To rotate the screw bar 24 I have provided on one end thereof a handle 30, and by rotating this handle in clockwise direction the clamps 27 are pulled inwardly in the direction of each other to contact with the side edges of the shoe sole to retain the shoe against accidental displacement from the 30 shoe plate 6 during the process of shining.

When the shoe shining operation is over, it is only necessary to rotate the handle 30 in counter-clockwise direction, which moves the clamps 27 away from one another and immediately frees the shoe.

When the device is applied as illustrated in Figure 2, and a person desiring a shine mounts the stand and places his feet on the plates 6, it is only necessary to take hold of the arm 12 and move it upwardly until it is 40 properly positioned beneath the plate 6 and the clamps are in position to seize the particular sized sole of the shoe. The handle 30 is then turned in clockwise direction and 45 the shoe clamped to the shoe plate 6 until

the shining operation is over and by a reversed motion of the handle 30 the shoe is released.

It is to be noted that the housing 21 has an area smaller than the width of the shoe plate 6, thus the entire device with the exception of the clamps 27 is located wholly within the plane of the area of the shoe plate 6. Thus, there are no parts of the device to interfere with the operation of the persons shining the shoes resting on the plate 6.

The function of the pivots 10 and 13, and springs 14, 16 and 17, is for the purpose of permitting the device as a whole to be adjusted to compensate for shoes having soles of various thicknesses.

Having thus described my invention, what I claim as new is:

1. In a foot rest and shoe clamp, the combination with a shoe supporting stand, of a pair of arms pivotally connected together and secured to said shoe stand, a shoe clamping means pivotally secured to one of said arms, spring means to hold said arms at substantially right angles to one another, and a second spring means secured to the stand and engaging said arm to normally urge said arms and clamp in the direction of said shoe stand.

2. In a foot rest and shoe clamp, the combination of a shoe supporting member having a sole and heel engaging portion, of a pair of arms pivotally connected together by one of their ends, means for pivotally securing one of the arms to the shoe stand, a shoe clamp pivotally secured to the free end of the other arm, spring means to support said arms at right angles to one another, spring means to normally urge the arms and clamp in the direction of the shoe supporting member, and means to operate said shoe clamp.

In testimony whereof he hereunto affixes his signature.

EMMETT W. ENTRIKEN.
